UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 28, 1921. Serial No. 488,067.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to a sound-deadening casing or hood for a typewriting machine, and is in the nature of improvements which may be used in connection with the parts shown in my co-pending application, No. 466,820, filed May 4, 1921 (now Patent No. 1,519,645 dated December 16, 1924), in which the line-space handle, carriage-return handle and carriage-release handle project from the casing through a slot between slot-closing means, and in which the keyboard section of the type-writing machine projects through an opening in the lower part of the casing, so that the machine may be operated from the exterior of the casing without lifting the cover.

More particularly, the invention relates to linings for such casings, which may be composed of felt or any other suitable sound-deadening material, and to the manner in which the lining is assembled and various parts thereof held in place within the casing. The parts are so constructed as to abut against each other to hold one another in place and to avoid, as much as possible, the use of separate fastening devices, such as screws; thus reducing to a minimum the time and material necessary to apply the lining to the casing.

Another feature of the invention is the provision of means to enable the work-sheet on the carriage to move freely therewith. To this end, the felt-lining at the back and top of the casing is covered with a layer of celluloid or any other suitable material which presents a smooth surface to the work-sheet where it is liable to engage the interior of the casing, thus preventing that drag on the paper or other displacement of the same, while the carriage is traveling, which might otherwise result were there a direct contact of the work-sheet with the usual rough surface of the felt lining.

A further feature of the invention relates to means for keeping closed the slot through which the various handles on the typewriter

carriage project; the slot-closing means comprising a cushion reinforced preferably by a coil-spring, and being held against a co-operative element by pressure-producing means, such as springs, arranged beneath the cushion.

Other features and advantages will hereinafter appear.

In the accompanying drawings, Figure 1 is a front view of the casing, partly in section, showing the arrangement of the pieces composing the felt lining, the section being taken on the line 1-1 of Figure 4.

Figure 2 is a top plan view of the casing with the cover removed.

Figure 3 is a detail side view, taken on the line 3-3 of Figure 1, of a portion of the cover, and shows how the felt lining of the cover extends downwardly along the side of the opening or window in the cover.

Figure 4 is a sectional side view of the casing taken substantially on the line 4-4 of Figure 1.

Figure 5 is a detail sectional view of a portion of the hood as seen from the front, the section being taken on the line 5-5 of Figure 4.

Figure 6 is a detail sectional view of a fragment of the slot-closing cushion.

The casing comprises a body part 10 to which a cover 11 is pivoted, which may be swung by means of a finger-piece 12 about a hinge 13 at the back of the casing. A slot is formed between the front end 14 of the cover and the upper edge 15 of a front wall of the body part, through which slot various handles, including a line-space handle 16, a carriage-release handle 17, and a carriage-return handle 18 may extend, so that the platen 20 of a typewriting machine 21 within the casing may be line-spaced, and the carriage 22 of said machine be returned or released without lifting the cover.

The body part and cover of the casing may be composed of outer shells 23 and 24, respectively, of thin metal or other suitable material, and may be reinforced by frames 25 and 26, to which the shells 23 and 24 may be secured, as indicated in my above-mentioned application.

The cover is provided with a closed window 27 bordered at its upper end by a cross-bar 28, which forms part of the reinforcing

frame 26, the window being framed and held in place between said bar and a front bar 30 by means of clamps 31. The bar 28 is shown as an angle bar, forming an offset inclined inward and rearward from the sheet-metal casing piece 11.

To enable the machine to be placed within the casing, the front wall of the body part 10 is provided with an opening bordered by end sections 32 of the front wall, and through which the keyboard section of the machine projects. A removable front plate 33 is provided, to close all of the front opening except that occupied by the machine, and may be fastened to the casing by slidible finger-pieces 34 having hooks 35 to engage studs 36 on the framework 25 of the body part; all as shown in my aforesaid co-pending application.

To locate the machine within the casing, abutments 40 are provided, which may engage the rear corner-posts 41 of the typewriting machine, said abutments being secured to the casing. After the machine is located, the front plate 33 may be assembled on the casing, said front plate being provided with abutments 42 oppositely disposed to the abutments 40 on the body part of the casing and engaging the front posts 43 of the machine (Figure 2), to clamp said machine in position within the casing.

The body part 10 of the casing has side walls 45, above which are overhanging lateral extensions 46 which, with the body part and cover, from an elongated chamber in which the carriage may travel to its extreme end positions. Depending from and at the rear of the carriage chamber are pockets 48 to provide clearance for the work-sheet 49, which hangs down at the back of the machine.

To assist in raising the cover 11, as disclosed in my aforesaid co-pending application, there may be provided counter-balance springs 50 connected to brackets 51 on the reinforcing frame 25 at the outer ends of the lateral extensions 46, said springs being connected through a linkage to the cover 11. The linkage may comprise a lever 52 pivoted on a bracket 78 also on the frame 25, said lever being connected by a link 53 to a bracket 54 secured to the reinforcing frame 26 of the cover.

More effectively to deaden the sound, the casing is provided with a felt lining formed in several parts, so that it may readily be assembled within the casing. The lining of the body part is composed of a rear or main section 60, which has two outward extensions 61, the bottom edges of the extensions 61 resting on the floors of the lateral extensions 46 of the carriage chamber and of the work-sheet pockets 48. The sides of the lower body part of the casing are provided with vertical pieces 62 having hori-

zontally-disposed portions 63 for the floors of the extensions 46, which may be cut, as indicated at 64, at the corners 65 thereof, for better shaping of the corners, and which may be reinforced by pins 66 to stiffen the corners.

The side pieces of felt 62 are held in place at their rear ends by the rear piece 60-61 which abuts the same; the horizontal portions 63 being held in place at their outer ends by strips of felt 67 disposed under the ledges 68 upon which the cover rests. The strips 67 overlie the horizontal portions 63 and by being downwardly pressed there against securely hold the portions 67 in position. The horizontal portions 63 rest at their forward edges against the framework of the front of the casing and may be secured thereto by screws 71. The vertical side pieces 62 likewise at their forward edges engage the front of the casing; and are there held flat against the casing side walls 45 by pieces 69 which line the front casing wall at each side of the removable front plate 33. The side pieces 62 have their lower edges on the angle bars of the sides of the base of the frame, and are there secured to the latter by screws 70.

As indicated at the left hand of Figure 1 and right hand of Figure 2, the pieces of felt 69 at the front of the casing are relatively narrow rectangular pieces extending from the lower front angle iron of the frame, upward along the front face of the casing between the vertical side pieces 62 and bars or frame pieces 84, which define the sides of the opening in the front of the casing, to a horizontal bar 83 which defines the lower line of the lateral overhang 46. These pieces 69 are pressed against the front wall under the bars 83, and between the vertical side pieces 62 and bars 84 and are thereby held in position. No screws or other means will ordinarily be required to secure the pieces 69.

The rear piece of felt 60 may be held against the back wall by the rear ends of the horizontal portions 63 and by right-angle lining pieces 72, which are set into the smaller pockets 48, and which abut the rear piece 60. The piece 60 may be further held at its upper and lower edges by screws 73 and 74, respectively.

The right-angle pieces 72 in the pockets 48 are shown in detail in Figure 5. It will be noted that, to obtain a better setting of these angle pieces in the pockets, they are cut away at their corners 73^a. To secure these pieces in place, pins 74^a may be pushed horizontally through their vertical portions and into the horizontal parts 63 of the side felt members; and pins 75 may be pushed vertically downward through the horizontal portions of the angle pieces 72 into the vertical parts 62 of the side pieces. Referring

to Figures 2 and 4, it will be seen that the front walls of the pockets 48 are provided with rectangular felt pieces 76, which are set in under and held at their upper edges by the overlapping rear edges of the horizontal floor pieces 63 at the places where the latter are cut away to accommodate the pockets 48. The vertical rectangular pocket-pieces 76 are also in part held in place by the right-angular pocket-pieces 72; between which latter and the front walls of the pockets 48 these vertical pieces 76 lie. The pieces 76 being relatively small, and being held along two edges by the right-angle pieces, and at the top by the side pieces 63, no screws or pins, or other retaining means, will ordinarily be required. The vertical portions of the right-angular pocket-pieces 72, at the upper edges thereof, assist the rear piece 60 in holding the floor pieces 63 in place.

As shown in Figures 2 and 4, the horizontal portions 63 are cut away at 77 at their outer ends to accommodate the springs 50 and the lower ends of the levers 52; these parts, as hereinbefore noted, operate to lift the cover. Suitable apertures 79 (see Figure 4) for the brackets 78 are also formed in the strips 67 which underlie the cover-supporting ledges 68 at the extreme sides of the overhang of the body frame. These strips 67 are also provided with apertures 80 for the brackets or arms 51 to which the cover-springs 50 are secured.

Slots or apertures are provided in the rear piece 60 to accommodate the arms of the rear abutment-members 40. Since, as indicated in Figure 2, the outside supporting arms of the abutment-members 40 pass through the vertical portions 62 of the side pieces, these latter are slotted or cut, as indicated at 82. No cutting of the rear piece 60 will ordinarily be required for the central rear brace-member 87, since, as indicated in Figures 2 and 4, the felt is sufficiently yieldable to accommodate this brace when the felt is forced into place.

The felt lining of the cover part may comprise a rear part 85 extending along the rear wall, and which curves upward and forward, and the forward edge 86 of which, at the rear of the hood-window, is seated in a corner formed by the offset cross-bar 28 and the ceiling 88 of the cover. In assembling the felt piece 85 in the hood, its edge 86 is first forced tightly against the bar 28 with the felt bent to the curvature of the cover, and the lower rear edge of the piece 85 is then secured by screws 89 threaded into the casing. On forcing the felt 85 against the bar 28, and due to the fact that the bar slants slightly inward and rearward, the forward edge 86 of the felt piece tends to be maintained in place without other holding means. The piece

of felt 85 on each side of the window is extended forward and downward along the ceiling of the cover, as indicated at 90 in Figure 3, and the extensions 90 are fastened at their forward ends by screws 91 to the front cross-bar 30 of the frame.

Two felt pieces 92 are provided, one for each side wall of the cover, these side pieces being held in place at their rear and upper edges (see right-hand section of Figure 1) by the piece 85 and its extensions 90, which form the lining for the cover-back and ceiling. The cover side pieces 92 may be secured in place against the side walls of the cover, at their forward and lower edges, by screws 93.

As indicated at 94 (see Figure 4), the work-sheet 49 hangs down behind the machine between the same and the wall formed by the felt pieces 60 and 85. If the work-sheet were allowed to have contact with the rough surface of the felt, the latter might drag on the work-sheet and disarrange or interfere with free movement of the same during movement of the carriage. To prevent this, there is provided at the rear of the cover a sheet 94 of material, such, for instance, as celluloid, having a smooth surface, which extends downward along the ceiling and back of the cover, and which may overlap another sheet 95 of similar material extending along the rear of the body part to a point thereof below the work-sheet pockets 48. Since the sheet 94 overlaps the sheet 95, the work-sheet cannot be caught between the two. The sheet 94 in the cover may be fastened at its upper and forward edge to the felt 85 by screws 96, and to the felt 85 near its lower edge by screws 97. The screws 73 which secure the upper edge of the lower rear piece 60 to the frame may serve to hold the lower celluloid sheet 95 in place.

More effectively to close the slot 100 through which the various handles on the carriage project, there is provided a slot-closing cushion 101 opposed to a co-operating element, such as a fixed metal bar 102. The cushion 101 is in the form of a fold of felt, leather or plush; the ends of the fold being clamped between two bars 103 and 104 secured to the front of the body part of the casing by screws 105. As indicated at the left hand of Figure 1, the cushion 101 makes a loop 106 under the operating lever 16, which loop is created, and advanced along the cushion, by the lever, as the carriage travels. The same condition is produced by handles 17 and 18. The cushion is reinforced and made resilient by a helical spring 107 extending through the cushion the full length thereof. The spring-containing fold of the cushion overhangs from the cushion-supporting bar 103, and thus may rock or be bent up

and down as and where the levers engage therewith. Suitable springs 108, disposed beneath the cushion and seated in holes 109 in an extension or offset 110 on the front 5 plate of the body part of the casing, serve to hold the cushion against its co-operating slot-closing bar 102 throughout its length, except where the cushion bends around the levers, thus closing the slot to prevent leakage of sound from within the casing.

Variations may be resorted to within the scope of the invention, and portions of the improvements may be used without others.

Having thus described my invention, I 15 claim:

1. A sound-deadening casing for a type-writing machine, having a body-part and a cover therefor, both having a sound-deadening lining, said cover comprising a window and a frame therefor, forming at its upper edge a downward offset in said cover, the cover-lining comprising a roof-strip secured at its rear to the cover and having its forward edge held in the corner formed 20 by the offset of the window-frame and the cover.

2. A sound-deadening casing for a type-writing machine, having a body-part and a cover therefor, both having a sound-deadening lining, said cover comprising a window and a frame therefor, forming at its upper edge a downward offset in said cover, the cover-lining comprising a roof-strip secured at its rear to the cover having its forward edge held in the corner formed by 30 the offset of the window-frame and the cover, said roof-strip having forward extensions on each side of the window-frame, and means for securing said extensions at 35 their forward ends.

3. A sound-deadening casing for a type-writing machine, comprising a body-part and a cover therefor, both having a sound-deadening lining, a shield of smooth material fixed to the inner face of the sound-deadening lining at the rear wall of the cover, and a shield overlapped by said first-mentioned shield, fixed to the sound-deadening lining at the rear of the body-portion 45 of the casing to prevent contact of a work-sheet with said lining during the typing operation.

4. A sound-deadening casing for a type-writing machine, comprising a body part 55 shaped to the outlines of the base of the machine and having lateral overhanging extensions in which the typewriter-carriage may have its throw; a cover for the casing having side walls and a roof which extends upward and forward; a sound-deadening lining for the casing comprising a piece for the rear of the cover, a piece for the rear of the body part, and pieces of smooth material to prevent contact of work-sheets

with said lining pieces; one of said smooth pieces being attached to the cover rear-lining piece and the other to the body part rear-lining piece, the upper of said smooth pieces overlapping the lower when the cover is closed to prevent catching of the 65 work-sheets between the two.

5. A sound-deadening casing for a type-writing machine having a carriage and an operating handle projecting therefrom, said casing having a slot through which said handle projects and along which it travels and comprising a flexible lip supported at one side of said slot for closing the same at 75 each side of said handle, and springs at short intervals supporting said lip in slot-closing position and permitting displacement of the lip by the handle to be local.

6. A sound-deadening casing for a type-writing machine having a carriage and an operating handle projecting forwardly therefrom, said casing having at its front a slot through which said handle projects and along which it travels and comprising a tube of flexible material supported at one side of said slot for closing the same at each 80 side of said handle, a helical spring inside said tube to hold it in the desired position in expanded and resitently flexible condition, and springs at short intervals supporting said tube in slot-closing position 85 except at the point of projection of the handle.

7. A sound-deadening casing for type-writing machines, slotted longitudinally at 90 the front for passage therethrough and movement therealong of an operating handle attached to the carriage of the machine within the casing, and comprising a cushion closing said slot except where the handle projects therethrough, said cushion comprising a fold of yieldable material and means within said fold to hold the cushion in expanded condition while permitting bending thereof, and springs set against the cushion at intervals therealong to hold 95 the same yieldable in slot-closing position and to localize the bending of said cushion by said handle.

8. A sound-deadening casing for type-writing machines, slotted longitudinally at 100 the front for passage therethrough and movement therealong of an operating handle attached to the carriage of the machine within the casing, and comprising a cushion closing said slot except where the handle projects therethrough, said cushion comprising a fold of yieldable material and a spring within said fold to hold the cushion in expanded and resitently flexible condition in desired position, means for clamping the edges of the fold in vertical position, a rail on which the neck of the fold rests with the cushion part suspended be-

yond the face of the rail to swing thereon as a pivot, and yieldable devices at intervals supporting the cushion part in slot-closing position except at the point of projection of the handle.

9. A sound-deadening casing for a type-writing machine, comprising a body-part, a cover hinged to the body-part at the rear, each of said parts having a lining of sound-deadening material on which the leading edge of a work-sheet delivered from the machine may catch, and a guide of smooth material in said cover fixed to the inner face of the sound-deadening lining thereof and conforming in shape to said lining to deflect the leading edge of said work-sheet and to prevent engagement of said leading edge with the cover-lining during typing operation, said guide extending below the hinged connection between said parts to prevent engagement of the leading edge of

the work-sheet with the body-part lining during the typing operation.

10. A sound-deadening casing having a shell, comprising a top arched at the rear and including a part inclined downwardly to the front, a window-frame in the downwardly-inclined part of the top, a sound-deadening lining comprising a sheet of sound-deadening material sprung into said arched portion with its forward edge abutting the window-frame and with its rear edge secured to said shell, and a shield extending rearwardly from said window-frame to prevent engagement of the sound-deadening material by work-sheets in the machine.

JOHN WALDHEIM.
